UNITED STATES PATENT OFFICE

2,426,507

SNOW REMOVAL APPARATUS

Robert James Inksetter, Copetown, Ontario,
Canada

Application March 23, 1945, Serial No. 584,380

1 Claim. (Cl. 37—43)

1

My invention relates to improvements in snow removal apparatus of the type wherein snow is dug by means of a rotatable digger member and ejected from the apparatus through a chute, and the object of my invention is to provide a rotatable digging member having its axis of rotation disposed substantially transversely of the direction of movement of the apparatus and provided with a plurality of peripheral digging teeth which bite into the snow and carry it around to a point where it is centrifugally ejected through the chute.

A further and particular object of my invention is to spray or otherwise deposit oil on the digging member to prevent snow from freezing or adhering to the member, and another object is to construct a very simple and effective apparatus wherein there is only a single main moving element for biting into the snow and carrying it to the ejection chute.

With the foregoing and other objects in view which shall hereinafter appear, my invention consists of an apparatus constructed and arranged all as hereinafter more particularly described and illustrated in the accompanying drawing, in which:

Figure 1 is a side elevational view of the apparatus.

Figure 2 is a vertical cross-sectional view through the apparatus.

Figure 3 is a front view, slightly reduced in size, and

Figure 4 is a reduced schematic side elevational view of a truck, showing my apparatus mounted thereon.

Like characters of reference indicate corresponding parts in the different views in the drawing.

The digging member of the apparatus consists of a substantially drum-shaped rotor 2 formed with a plurality of grooves 3 in its periphery wherein the faces 4 of the grooves constitute the digging teeth. Upon reference to Figures 1 and 2 of the drawing, it will be seen that each portion 5 of the face of the drum extending counterclockwise from a digging face 4 to the next groove is off centre to the axis of the drum and has a smaller radius than the radius of the drum, so that the outer edges 6 of the digging faces are in the form of projections.

It will also be seen upon reference to Figure 2 of the drawing that each digging face 4 is inclined in relation to the radius line A extending from the axis of the member 2 to the outer edge 6 of the face so that the teeth are formed to dig 55

into the snow. Each face 4 is preferably fitted with a hard steel tooth plate 7.

The drum 2 is carried upon a transverse shaft 8 supported within an open front housing 9, the bottom rear face 10 of which is curved to be close to and conform with the rotative path of the edges 6 of the teeth. A chute 11 extends upwardly from the housing 9 and is so positioned that the snow lodging in the grooves 3 is centrifugally projected into the tangential chute. As will be seen upon reference to Figure 3, the chute is preferably inclined to one side, so as not to interfere with the field of vision of the driver operating the truck or tractor upon which my apparatus may be mounted.

Where there is a possibility of deep snow being encountered, an upwardly swingable horizontal plate 12 may be pivotally mounted upon the upper front edge of the housing 9. The plate carries 20 a number of downwardly projecting snow-engaging prongs 13 which are mounted rearwardly of an upwardly curved lip 14 formed on the front edge of the plate 12. The prongs are designed to break into deep snow and smash the snow's crust 25 as the apparatus moves forwardly. In encountering very deep snow, the plate 12 can swing upwardly. A forwardly projecting ground-engaging shoe 15 is supported upon the lower forward edge of the housing 9.

30 My apparatus can be mounted upon any suitable type of vehicle and driven in any suitable manner. For example, in Figure 4, I show the apparatus mounted upon a truck 16. The truck is shown carrying a suitable apparatus supporting frame which incorporates two pairs of channel members 17 and 18 to which the apparatus is attached in front of the truck.

To rotate the rotor 2, the ends of the shaft 8 project through bearings carried upon the sides 40 of the housing 9 and carry worm gears 19 which mesh with worms 20 carried upon the forward ends of a pair of horizontal drive shafts 21. The gears are contained within housings 22.

The drive shafts 21 are connected to a motor 23 mounted upon the truck 16, and any suitable type of driving connection can be used, such as a pair of horizontal shafts 24 extending along the base of the frame from the apparatus to the motor, the shafts 24 being connected to the shafts 21 and to the motor by driving chains and sprockets 25 and 26. In order to prevent snow from freezing or otherwise adhering to the grooves 3 of the rotor, I spray oil on to the rotor and into the grooves 3 as the rotor rotates. This is accomplished by carrying an

oil containing tank 27 on the truck, from which oil is pumped through a pump 28 and piping 29 to a plurality of nozzles 30 in the housing 9, as shown in Figures 2 and 3. Any low temperature free flowing type of oil can be used, for example, used oil taken from automobile crank cases, which is generally quite dilute and can be obtained at little or no cost. The use of oil to automatically coat the snow digging surfaces of the apparatus is a very important feature in that it will overcome the snow clogging difficulties that are encountered in all types of power driven snow digging appliances. The speed of my rotor 2 will depend upon the particular snow conditions, but should preferably be maintained at sufficient velocity to centrifugally eject the snow from the grooves 3 through the tangentially positioned chute 11.

From the foregoing description, it will be seen that I have devised a particularly simple and efficient snow removal apparatus, and, while I have shown a particular embodiment of my invention, it is to be understood that I can make such changes and alterations as I may from time to time deem necessary, without departing from the spirit of my invention as set forth in the appended claim.

What I claim as my invention is:

A snow removal apparatus of the character described comprising a rotatable digging member having its axis of rotation disposed substantially transversely of the direction of movement of the apparatus and formed with a plurality of grooves in its periphery which extend substantially parallel to the axis of the member,

one face of each groove forming a digging tooth, the outer edges of the digging tooth faces of the grooves being of greater distance from the centre of rotation of the rotatable digging member than the outer edges of the non-digging faces of the grooves, a snow ejection chute extending upwardly from the rear portion of the rotatable digging member in a substantially tangential direction in relation to the rotative path 10 of the digging member, the digging member being positioned underneath the chute, and an oil ejection nozzle positioned forwardly of the chute and so directed that oil ejected from the nozzle strikes the snow engaging faces of the 15 rotating digging member after such faces pass from underneath the chute, and means for ejecting oil through the nozzle under pressure.

ROBERT JAMES INKSETTER.
